LADY'S HAIR ORNAMENT

Siegfried Behr, Flushing, N. Y.

Application August 22, 1956, Serial No. 42,696

Term of patent 3½ years

(Cl. D86—10)

Fig. 1 is a top plan view of a lady's hair ornament showing my new design.

Fig. 2 is a front elevational view thereof.

I claim:

The ornamental design for a lady's hair ornament, as shown.
